CLAIM

The ornamental design for a nozzle, as shown and described.

DESCRIPTION

Cross reference is made to co-pending U.S. patent application Ser. No. 29/326,959, entitled "Nozzle" by William F. Zore, which was filed on Oct. 28, 2008 and is assigned to the same assignee of the present invention. The above-identified patent application is herein incorporated by reference in its entirety.

FIG. 1 is a perspective view of a nozzle showing my new design;

FIG. 2 is a left side elevational view showing the design for the nozzle of FIG. 1;

FIG. 3 is a right side elevational view showing the design for the nozzle of FIG. 1;

FIG. 4 is a front elevational view showing the design for the nozzle of FIG. 1;

FIG. 5 is a rear elevational view showing the design for the nozzle of FIG. 1;

FIG. 6 is a top elevational view showing the design for the nozzle of FIG. 1; and,

FIG. 7 is a bottom elevational view showing the design for the nozzle of FIG. 1.

The broken line showing of portions of the nozzle is included for illustrative purposes only and forms no part of the claimed design.
